UNITED STATES PATENT OFFICE.

JOHN S. MYERS, OF PHILADELPHIA, PENNSYLVANIA, ASSIGNOR TO WESTINGHOUSE ELECTRIC & MANUFACTURING COMPANY, A CORPORATION OF PENNSYLVANIA.

GEAR PUMP.

Application filed November 19, 1924. Serial No. 750,806.

My invention relates to gear pumps and in particular to that form of gear pump in which a worm is employed to cooperate with the gear.

5 In the ordinary form of gear pump in which gears, meshing with each other, are employed, there is a loss due to the facts that the fluid to be pumped is trapped between the teeth of the gears and must be
10 forced out through comparatively small openings, thus producing a back-pressure and that fluid is prevented from properly entering on the suction side when the teeth begin to disengage, thus producing a partial
15 vacuum. These factors reduce the efficiency of the pump and are prevented in my device by the use of a worm as a barrier to prevent the translation of liquid completely around the worm gear. The worm engages the gear
20 with a sliding contact and no liquid is trapped between the teeth of the worm gear and worm, but the fluid is swept out, and on the suction side the fluid is admitted gradually to the gear.
25 One of the objects of my invention is to provide a pump in which the use of check and other valves is dispensed with, and in which all passages for the liquid are relatively large, unimpeded by valves, and have
30 as few abrupt changes in the direction as possible so that the danger of clogging is reduced to a minimum, and which operate smoothly and with a low loss of power. A further object is to produce a pump in which
35 no liquid is trapped between the gear and the worm or in which no partial vacuum is produced by the withdrawal of teeth from the tooth spaces not in communication with the supply. A still further object is to produce a device of the character described
40 which shall be efficient, simple in operation, easy of construction, and which permits ready assembly or disassembly.

45 These and other objects of my invention will be apparent from the following description, having reference to the accompanying drawings in which Fig. 1 is a vertical section of one preferred embodiment of my invention taken on the line I—I of Fig. 2; Fig. 50 2 is a horizontal section taken on the line II—II of Fig. 1; Fig. 3 is a sectional view similar to Fig. 1 but illustrating another embodiment of my invention; Fig. 4 is a horizontal section taken on line IV—IV of Fig. 5, showing a still further embodiment

of my invention; Fig. 5 is a vertical section taken on line V—V of Fig. 4; and Fig. 6 is a view similar to Fig. 1 showing a modification of a detail of my device.

Referring first to Figs. 1 and 2, I show a gear pump 10 comprising an upper casing 11, a lower casing 12, a worm 13, and four gears 14 completely surrounding the worm. The worm 13 is of a type commonly known as the Hindley worm, which is characterized by the fact that it is cut on a solid of such form that if any plane be taken through its longitudinal axis, the intersections of the plane by the perimeter are arcs of the pitch circle of the gear wheel into which the worm is intended to work. The worm 13 is driven by a shaft 16 which is held against longitudinal movement by a thrust bearing 17. The worm, in turn, drives worm gears 14, which are mounted on shafts 19 and which rotate in the direction shown by the arrows in Fig. 1. The shafts 19 rest in semi-cylindrical recesses 21 in the upper and lower casings 11 and 12. The casings are held together by bolts 23, passing through lugs 24 on the casings 11 and 12. Should it be necessary, in order to secure a tight joint between the casings 11 and 12, the lugs could be extended completely around the edge of the casings as a flange or an additional number of lugs could be provided. The fluid to be pumped is supplied to the pump through a suitable conduit 27 communicating with the admission chamber 28 in the lower casing. The fluid is then entrained between the teeth 29 of the worm gears and the wall 31 of the casing and is swept around by the teeth to the delivery chamber 33 which is in communication with a discharge conduit 34. Due to the fact that the gears completely surround the worm only a very small amount of liquid leaks back to the chamber 28. Should any fluid seep around the shaft 16, it is collected at the chamber 36 and returned to chamber 28 through a pipe 39. If the fluid pumped is oil the thrust bearing 17 is placed in the chamber 36 as shown in Fig. 6. In Fig. 3 I show a modification of my pump in which a straight worm is used. This permits the worm to be longer than is possible with a Hindley worm, thereby permitting the thrust to be taken up by a bearing 41. With this form of worm the bottom portion is bored out to form a recess 42 into which the fluid flows and from

which it is delivered to the worm gears 14 through openings 44. It is of course, understood that in this embodiment the worm is completely surrounded by gears as shown in Fig. 2.

In Figs. 4 and 5, I show a further modification of my invention. In this form the fluid is propelled by the worm 13' instead of by the gear, the gear 51 serving as a traveling barrier or gate. The worm 13' is of the hour glass or Hindley type, similar to the worm 13 of Fig. 1. The gear 51 will operate in the direction shown by the arrow in Fig. 5 which is the opposite direction to that in which the gears 14 of Fig. 1 operate. This embodiment is less efficient than the preceding embodiments due to the fact that some oil will be carried back between the gear 51 and the casing 11' and 12'. However, by making this worm gear relatively thin this amount is greatly reduced. In this form of my device, the fluid enters at 27', flows upwardly into the chamber 28' and is forced upwardly by the worm 13' from whence it is collected in the chamber 33' and delivered to the discharge conduit 34'.

While my invention is capable of wide application, I have found it particularly adapted for use as an oil pump in supplying fluid under pressure for lubrication and to fluid pressure actuated governors for rotating devices such, for example, as steam turbines. Furthermore, by applying fluid under pressure to the suction of the pump,

the fluid will cause a rotation of the gears and the device will operate as a fluid motor, power being delivered to the shaft of the worm or to one or all of the shafts of the worm wheels.

Although I have illustrated four worm wheels a lesser or greater number may be used, the object being to embrace the complete circumference of the worm.

While I have shown my invention in several forms, it will be obvious to those skilled in the art that it is not so limited, but is susceptible of various other changes and modifications, without departing from the spirit thereof, and I desire, therefore, that only such limitations shall be placed thereupon as are imposed by the prior art, or as are specifically set forth in the appended claims.

What I claim is:

1. In a fluid translating device, the combination of a worm, and gears meshing with the worm and having laterally abutting teeth, said teeth being arranged to completely encompass the worm.
2. In a fluid translating device, the combination of a worm, and gears meshing with the worm and having their lateral edges beveled substantially on radii of the worm, the beveled edges being juxtaposed substantially in working contact.

In testimony whereof, I have hereunto subscribed my name this twelfth day of November, 1924.

JOHN S. MYERS.
